UNITED STATES PATENT OFFICE.

NOAH HALE, OF CHATTANOOGA, TENNESSEE, ASSIGNOR TO HENRY LOEB AND HENRY HURST, BOTH OF MEMPHIS, TENNESSEE.

OIL BURNER.

Application filed June 17, 1921. Serial No. 478,278.

To all whom it may concern:

Be it known that I, NOAH HALE, a citizen of the United States, residing at Chattanooga, in the county of Hamilton and State of Tennessee, have invented certain new and useful Improvements in Oil Burners, of which the following is a specification.

My said invention relates to an oil burner provided with improved means for vaporizing oil and is intended to be used primarily in cook stoves and ranges for cooking food, heating water and the like. It is an object of my invention to provide improved means for heating water in the water back of a kitchen range.

Another object of my invention is the provision of improved means for automatically regulating the admission of air in a fixed ratio to the amount of oil vapor admitted to the burner.

A further object is to provide improved means for starting the burner.

Referring to the accompanying drawings which are made a part hereof and on which similar reference characters indicate similar parts,

Figure 1 is a side elevation of my improved device,

Figure 2 a plan view thereof, and

Figure 3 a section on line 3—3 of Figure 2.

Fig. 4 is a side view of a modified form of starting burner.

Fig. 5 is a sectional view of the jet nozzle of the starting burner.

In the drawings reference characters 5 and 6 indicate respectively the upper and lower members of the outer shell of the burner, these members having outwardly extending flanges connected by bolts 7 in the usual manner and provided with an asbestos gasket 8 of usual form to prevent leakage. The upper member is formed with ridges or corrugations having at their highest points ignition slots 9 extending therethrough, the upper margins of the ridges acting as lips for the ignition slots, and the ribs being separated by transverse de-

pressions 10.

A baffle in the form of a flat plate 11 extends horizontally across the one chamber of the shell and is supported at the level of the joint between the members 5 and 6 by a reduced flange engaging between them. This

baffle has a row of holes 12 at intervals running about one-half its length and an elongated opening 13 positioned in the rear of said holes, extending longitudinally of the plate and widening toward its rear end. Said opening, as well as the holes 12, is preferably made so as to flare upwardly.

At its rear end the member 5 has a pan 14 and a passage 15 extending forward from the pan. I have shown the pan and the walls of the passage as being integral with the member 5 though they may be formed separately and attached thereto. A perforated member 16 is inserted in the forward end of passage 15 and extends therefrom to the forward end of the burner. I prefer to make this member of wire screen, though it may be formed of perforated sheet metal or otherwise.

At one side of the member 5 I attach thereto or form integral therewith a tray or receptacle 17 in which a loose mass of asbestos is intended to be placed, said mass acting as a wick that may extend into or be moistened with gasoline or other liquid fuel. Extending partially within this tray is a coil 18 terminating in a valve 19 in the end of which is loosely inserted a movable member 20 having at its lower end a corkscrew formation. The member 20 will rotate and move up and down in the passage of member 19 under pressure of fuel and keep the opening free from carbon and dirt at the same time insuring proper spray and combustion of fuel due to its up and down and rotary movement. Preferably the coil is bent to a triangular shape as at 18' in Figure 4, as this increases the heating effect and secures better vaporization. A flame spreader 21 formed as a bent plate to cover the coil and having downwardly projecting sides to cause the flame to act on all sides of the main coil rests at its lower edges on the tray and extends over the coil 18 and is fastened to an upwardly projecting flange of member 6 by a screw at 22. Any unvapORIZED oil dripping from valve 19 will be caught by the tray, which may be provided with means for draining it, if desired.

Fuel may be admitted to the coil 18 from a pipe 23 by a valve 24 having a knurled head 24'. A second valve 25 having a knurled head 25' is provided to admit liquid fuel to the vaporizing coil 26 extending from one end of the casing to the other and back

again. The latter valve leads to a small pipe 27 which is connected by a reducing elbow 28 to coil 26, and the coil 26 at its opposite end is threaded to the stem of a T-joint forming the barrel of the rotary main spray-valve 29. The stem 30 of this valve extends through the body 29 and has threaded connection therewith at 31, and the conical forward end of the same engages a correspondingly tapered seat at 32 held in place by a flanged nut threaded on the barrel. At the rear end of the valve body is a flanged nut 33 holding a packing in place about the valve stem 30 which has a knurled head 34. The coil 26 has within it a bundle of retarding filaments 26' which gradually tapers from a bundle nearly filling the tube beneath the flame spreader 21 to a single filament lying more or less near the fuel feed valve 25. A similar bundle of filaments 43 or 43' is preferably used in coil 18 or 18' for a similar purpose.

An arm 35 extends at right angles to the stem of the valve 34 and is connected by a link 36 to a pivoted cover 37 adapted when the valve is closed to rest on the combined air intake and catch-basin 14 and as the valve stem is turned to open the valve the cover is raised to admit more air to the mixer. Downwardly extending projections 38 and 39 extend across the lower member 5 and serve as supports for the entire device.

In the operation of my vaporizing device liquid fuel is first poured into the tray 17 where it is taken up by the wick and may then be set on fire. After this has been lighted the valve 24 is opened to feed oil to the coil 18 by turning the knurled head 24' and the fuel flows through the coil and lifts up and rotates the corkscrew device 20. The oil in the coil will become vaporized by the heat and the vapor passing through the valve 19 will become ignited and the flame therefrom will be spread by the spreader 21 over the coil 26. Before combustion has proceeded so far fuel will have been admitted to pipe 27 and coil 26 by turning head 25' of valve 25 and the vaporizing coil 26 will be filled with liquid fuel except for the space occupied by the filaments 26'. Vaporization of the fuel is assisted by the heating of the filaments 26' to which heat is conducted from the surface of the coil 26, the heat being carried back through the coil in this manner for some distance to gradually warm the fuel and assist in vaporization. When the coil 26 is sufficiently heated the main spray valve is opened by turning the head 34 and this admits volatilized fuel to the passage 15 and at the same time lifts the cover 37 to admit air thereto. Any unvolatilized fuel admitted to the passage 15 will collect in the bottom of the same and in the catch-basin 14 from which it can be drained off in any convenient manner. The

heated spray of volatilized fuel passing forward through the passage will go through the perforated tube 16 and rise therefrom. Part of the fuel will pass through openings 12 and part through the slot 13 which is made narrow at the front to cause some of the fuel to pass to the rear. The general form and arrangement of the openings is well adapted to distribute the fuel evenly under the entire surface of the member 6. As the fuel issues from the slots 9 it will burn uniformly over the upper surface of the device and will continue to heat and vaporize the fuel in the coil 26. After vaporization is well started in the coil 26 the fuel is turned off from coil 18.

When my device is to be used in connection with a range having a water-back or front holes are drilled at 40 at the lower ends of the grooves 10, and at the proper side of the member 6 to give the desired results.

I may combine with the mechanically operated air valve an automatically controlled valve as by providing one or more openings 41 in the rear wall of the pan 14 with a normally closed gate or gates 42. As the gas is turned on the draft will open the gates if sufficient air is not supplied by the valve 37. The link 36 may be arranged to unhook from eye 35, if desired, so that only the automatic valve will be in use, or the valve 37 may be entirely omitted.

Having thus fully described my said invention, what I claim as new and desire to secure by Letters Patent, is:

1. A burner comprising, an elongated chamber having transverse ignition slots at the top, a perforated baffle plate dividing the chamber into upper and lower portions, a minutely perforated tube below the baffle plate and means for admitting vaporized fuel to pass successively through said tube and baffle to the ignition slots, substantially as set forth.

2. A liquid fuel burner comprising, an elongated chamber having transverse ignition slots at the top, a perforated baffle plate dividing the chamber into upper and lower portions, a tube of wire screen beneath said baffle plate, and means for admitting vaporized fuel to pass successively through said tube and baffle to the ignition slots, substantially as set forth.

3. A liquid fuel burner comprising an elongated chamber, a perforated horizontal baffle plate, an upper member above said plate having transverse ignition slots and transverse grooves between them and ignition openings at the lower end of said grooves at one side of the burner, substantially as set forth.

4. A liquid fuel burner comprising an upper member having ignition openings, a vaporizing coil extending over said openings, a valve to admit fuel thereto, a valve to

transmit vaporized fuel therefrom to the interior of the burner, means for initially heating a portion of the coil including a helical auxiliary coil and a valve for admitting fuel thereto, and means for heating the outlet end of the auxiliary coil, each of said coils including a bundle of metallic filaments of varying lengths so as to taper from the outlet end back toward the inlet end of each

10 coil, substantially as set forth.

5 5. A liquid fuel burner comprising an upper member having ignition openings, a feed coil extending over said openings, a valve to admit fuel thereto, a valve to transmit vaporized fuel therefrom to the interior of the burner, means for initially heating a portion of the coil including a pan, an auxiliary triangular coil having one angle extending downward into the pan, a valve admitting fuel to the coil and a valve at the end of the coil for controlling the feed of fuel therefrom, substantially as set forth.

15 6. A liquid fuel burner comprising an upper member having ignition openings, a feed coil extending over said openings, a rotary valve to admit fuel thereto, a rotary valve to transmit vaporized fuel therefrom to the interior of the burner, means for initially heating a portion of the coil including an auxiliary coil, a valve having a hollow sleeve and a plunger having at its lower end a corkscrew formation, said plunger being adapted to move up and down and also to rotate under the pressure of the fuel, substantially as

30 35 set forth.

7. A liquid fuel burner comprising a heating surface, a feed pipe forming a coil over said surface and bent vertically downward at the outlet end, means for initially heat-

ing a portion of the coil including a flame spreader extending over a portion of the coil, heating means beneath the spreader, and a bundle of loose incombustible filaments of varying lengths in said coil extending from the locality of said flame spreader toward the source of fuel, the bundle of filaments tapering from the locality of the spreader toward the source of fuel, substantially as set forth.

8. A liquid fuel burner comprising a chamber for vaporized fuel and an ignition surface above the chamber and communicating therewith, means for supplying fuel to the chamber, a valve for controlling the supply of fuel to the chamber, a pan beneath the valve, said pan also forming a passageway for air, a cover for said pan regulating the passage of air and means for simultaneously operating said valve and said cover, substantially as set forth.
